RIVETING MACHINE

Fred A. Howard, Kenmore, N. Y.

Application April 18, 1936, Serial No. 75,161

10 Claims.

(Cl. 218—2)

My invention relates to pneumatic riveting machines of the portable type and more particularly to improvements in rivet feeding and setting mechanism therefor.

5 The principal object of my invention is to provide an efficient machine of this character which is adapted to drive various types and sizes of rivets with greater speed than riveting machines of commerce without damage to the rivets such 10 as frequently occurs in present day machines, for instance, burning the rivets, driving them sideways, splitting or marking the heads thereof, and without necessitating adjustment of the hammer mechanism when changing from rivets 15 of one size to another.

Another object is to provide improved means for feeding and setting rivets of various sizes relative to the driver of a pneumatic hammer.

Still another object is to provide improved setting means for the rivets adapted to release the rivets under control of the hammer mechanism so that they are freed while being driven thereby obviating burning or other injury from friction.

25 Other and subordinate objects together with the advantages of my improvements will be readily understood when the following description and claims are read with reference to the accompanying drawings.

30 In said drawings:

Figure 1 is a view in side elevation, with parts broken away, of a riveting machine equipped with my improvements.

Figure 2 is a view of the riveting machine in 35 rear elevation.

Figure 3 is a view of the riveting machine in top plan.

Figure 4 is a fragmentary view partly in vertical transverse section and partly in side elevation of 40 a feed hopper and distributing means with which the machine is equipped.

Figure 5 is a fragmentary view partly in vertical section taken on the line 5—5 of Figure 2 looking in the direction indicated by the arrows.

45 Figure 6 is a detail view in transverse section taken on the line 6—6 of Figure 2 looking in the direction indicated by the arrows and drawn to an enlarged scale.

50 Figure 7 is a similar view taken on the line 1—1 of Figure 2 looking in the direction indicated by the arrows.

Figure 8 is a detail view in top plan of a pair 55 of rivet holding jaws with which the machine is equipped, and

Figure 9 is a view in side elevation of one of said jaws.

Describing my invention in detail with reference to the accompanying drawings, the numeral 1 designates generally the hammer mechanism of the machine. Since the details of the hammer mechanism per se form no part of the present invention, said mechanism has merely been illustrated conventionally in the drawings. Suffice it to explain that said mechanism includes the 10 usual housing cylinder 2 having a handle 3. The piston or plunger is indicated at 4, the driver or punch at 5 and the air trigger at 6. The piston or plunger 4, as will be understood, is pneumatically driven but the air connections to the 15 casing 2 have not been shown since they are not necessary to a proper understanding of the invention.

Coming now to my novel improvements, secured to lugs 7 on the housing 2 as by screw bolts 8 to extend longitudinally of the housing is a rivet feeding chute 9 comprising a pair of plates 10 and a laterally spaced side plate 11 extending slightly above said housing. At its lower end the chute 9 inclines toward the driving punch 5 to a point adjacent the same and is provided with rearwardly disposed extensions 12 on the plates 10. Liners or adapter strips 13 corresponding in shape to the chute are removably secured to the plates 10 to provide a channel 14 substantially T-shaped in cross section for a purpose presently clear.

Surmounting the upper end of the chute 9 is a supply hopper 15 secured to said chute by means of a plate 16 bolted to the chute as at 17 and to the hopper as at 18. The hopper 15 comprises a supply receptacle 19 having a hinged cover 20 and a cylindrical casing 21 opposed to the hopper and open at its side opposite the latter. The hopper is provided with a sleeve 22 extending from one wall thereof axially of the casing 21 and in which is rotatably mounted a stud 23 having a collar 24 thereon bearing against one end of said sleeve. At one end the stud 23 is journaled as at 25 in a bracket 25' for rotation 40 therein. The end 25 of the stud may be threaded or otherwise mounted in the stud 23. A frustoconical distributor wheel 26 is rotatably mounted in the casing 21. Said wheel is provided with a series of radially disposed slots 27 arranged on the surface thereof and a cylindrical part 28 into which said slots open, journaled on the stud 23 and adapted to be clamped against the collar 24 by a wing nut 28. The bracket 25' is slidably mounted as by slot and pin connection 29 and 30 50

on the wall of the hopper 15 and urged by a spring 31 against the stud 23 to act as a friction brake. The arrangement of the slots 27 of the distributor wheel 26 is such that upon rotation 5 of said wheel rivets will be taken from the hopper and the shanks thereof disposed in said slots and dropped into the upper and open end 32 of the chute 9 with their heads in the channel 14. Said wheel 26 being clamped against the collar 24 by 10 the wing nut 28, by turning said nut the wheel may be rotated as desired.

Located at a suitable point above the bottom end of the chute 9 is an escapement feed device 33 pivotally mounted as at 34 on the front wall 15 of the chute for oscillating movement and comprising upper and lower arms 35 and 36, respectively, adapted to play in slots 37 in the side walls 11 of the chute 9. A suitably arranged spring 38 tensions the escapement feed device 33 so 20 that the upper of said arms normally intercepts the passage of the rivet down said channel 14. Pivotally mounted upon the front wall of the chute 9 as at 39 is an escapement rocking lever 40 the forward end of which underlies the piston 4 and 25 the other end of which underlies one side of said device 33.

At the lower inclined end of the chute is a pair 30 of opposed rivet holding jaws 41 mounted upon resilient arms 42 suitably secured to the lower end of the chute 9 for relative separative movement of the jaws 41 laterally. The jaws 41 are constructed so that in their normal position they form a funnel shaped socket 43 beneath the punch 5 slightly larger at its mouth than said punch. 35 The socket 43 is provided with a transverse groove 44 forming a continuation of the channel 14 and designed to receive the head of the rivet discharged from said channel.

Mounted between the extensions 12 of the plates 40 10 is a reciprocating rivet holding and releasing arm 45 the forward end of which is designed to underlie the head of the rivet located between the jaws 41 to clamp the rivet in said socket and release it at the proper time. Preferably the arm 45 is mounted upon a stud 46 and slotted arcuately as at 47 and its rear end is guided during reciprocatory movement by a pin 48 thereon passing through a straight slot 49 in one of the extensions 12. The arrangement of the slots 47, 49 50 and the studs 46 and 48 is such that the arm will be advanced forwardly and downwardly as will be clear. Pivotally mounted upon the pivot 39 of the escapement operating lever 40 is an arm operating lever 49a operatively connected to the rear end of the holding arm 45 by a compensating pin and slot connection 48 and 51, respectively, and having one end underlying the piston 4. A helical spring 52 having its opposite ends connected to said lever and to said extension as at 53 and 54, respectively, normally urges the lever and arm into an advanced rivet holding position. The arm 45 is designed to be latched in retracted position and for this purpose is provided with a right angled rear end 55 cooperating with 60 a latch 56 pivoted as at 56' between the extensions 12 and tensioned by a spring 58 so that it is normally in the path of movement of the end 55. Associated with the latch 56 is a latch releasing lever 59 pivotally mounted as at 60 upon a bracket 61 suitably secured to one of the extensions 12. The latch releasing lever 59 comprises a latch releasing arm 62 adapted to be swung against said latch to move the same against the urge of the spring 58 and a manually manipulative end 63 extending adjacent to the air trigger 6.

Referring now to the operation of my invention, the rivets dropped into the chute 9 by the distributor wheel 26 in the manner previously described are intercepted by the escapement feed device 33. The arm 45 when starting the machine is latched in retracted position and the escapement feed device is manually rocked once under which operation a rivet escapes into the socket 44. The latch releasing arm is then operated to permit the advance of the arm 45 to rivet holding position and the rivet placed in the hole. The air trigger 6 is now operated. Immediately following operation of the trigger the arm 45 is retracted to release the rivet and latched in retracted position. The driving punch 5 enters the socket 44 and the jaws 41 are separated laterally by the punch 5 to release the rivet. During this separative action the escapement device has been cocked by the operation of the lever 40 by the piston 4 for operation under the action 20 of the spring 38 to permit another rivet to descend into the socket 44. Upon simultaneous operation of the air trigger 6 and latch releasing lever 59 the foregoing operations are repeated.

By removing the liner or adapter strips 13 25 and substituting others of different gauge therefor larger or smaller rivets may be handled as desired. The entire chute 9 and hopper 15 may be detached from the position shown and attached to said housing on the other side thereof on lugs 30 64 provided on the other side of the housing for that purpose for left-hand work. Under these conditions the latch releasing lever 63 is reversed and attached to a lug 64' on the opposite side of the chute 9.

The foregoing is a detailed description of a preferred embodiment of my invention, but it is to be understood that right is herein reserved to changes and modifications in the details and relation of parts described falling within the scope 40 of the protection prayed.

What I claim is:

1. In a machine of the class described, the combination with a driving punch, of means for feeding rivets to a position in axial alignment with said punch and holding said rivets in such position, and including a pair of cooperating rivet holding jaws relatively separable laterally under the action of said punch and releasable holding means engaging between said jaws.

2. In a machine of the class described, the combination with a piston and a driving punch, of means for feeding rivets to a position in axial alignment with said punch and holding said rivets in such position and including a pair of 55 cooperating rivet holding jaws relatively separable laterally under the action of said punch, and means for holding the rivets in said jaws movable to releasing position by said piston prior to separation of said jaws.

3. In a machine of the class described, the combination with a driving punch, of means for feeding rivets to a position in axial alignment with said punch and holding said rivets in such position and including a pair of cooperating rivet holding jaws relatively separable laterally to release the rivets as an incident to operation of said punch, and releasable rivet holding means engaging between said jaws.

4. In a machine of the class described, the combination with a piston and a driving punch, of means for feeding rivets to a position in axial alignment with said punch and holding said rivets in such position and comprising, a gravity feed chute, a pair of cooperating rivet holding 75

5 jaws for receiving the rivets from said chute therebetween and relatively separable under the action of said punch to free said rivets, and means to hold the rivets in said jaws comprising a holding arm operative to releasing position by the piston.

10 5. In a machine of the class described, the combination with a piston and a driving punch, of means for feeding rivets to a position in axial alignment with said punch and holding said rivets in such position and comprising, a gravity feed chute, a pair of cooperating rivet holding jaws for receiving the rivets from said chute therebetween and relatively separable under the action 15 of said punch to free said rivets, means to hold the rivets in said jaws comprising a holding arm operative to releasing position by the piston, and a latch for holding said arm in releasing position.

20 6. In a machine of the class described, the combination with a piston, and a driving punch, of means for feeding rivets to a position in axial alignment with said punch and holding said rivets in such position and comprising, a gravity feed chute, a pair of cooperating rivet holding jaws 25 for receiving the rivets from said chute therebetween and relatively separable under the action of said punch to free said rivets, and means to hold the rivets in said jaws and comprising a holding arm tensioned for movement to effective position and movable to ineffective position under control of said piston, a latch for holding said arm in ineffective position, and manipulative means for rendering the latch ineffective at will.

30 7. In a machine of the class described, the combination with a piston, and a driving punch, of means for feeding rivets to a position in axial alignment with said punch and holding said rivets in such position and comprising, a gravity feed chute, a pair of cooperating jaws for receiving the rivets from said chute therebetween and having relative separating movement as an incident to operation of said punch, and means to hold the rivets in said jaws comprising a holding arm disposed between said jaws and movable to effective and ineffective positions, respectively, said arm being tensioned for movement to one

of said positions and movable to the other position under control of said piston, a latch for holding the arm in one of said positions, and manipulative means for rendering the latch ineffective at will.

5

8. In a machine of the class described, the combination with a piston, a driving punch, and a trigger arm, of means for feeding rivets to a position in axial alignment with said punch and holding said rivets in such position and comprising, a pair of rivet holding jaws having relative separating movement as an incident to operation of said punch, means to hold the rivets in said jaws comprising a holding arm disposed between the jaws and movable to effective and ineffective positions, respectively, said arm being tensioned for movement to one of said positions and movable to the other position under control of said piston, a latch for holding the arm in one of said positions, and a latch releasing lever extending to a point adjacent the trigger arm for operation by the latter.

10

9. In a machine of the class described, the combination with a punch, and a piston, of means for feeding rivets to a position in axial alignment with said punch and comprising, a gravity feed chute, an escapement device adapted to intercept the passage of the rivets through said chute and comprising a toothed plate extending into said chute and mounted for oscillating movement under control of said piston, and means connected to said escapement device and in the path of the movement of said piston to thereby operate said escapement device.

20

10. In a machine of the class described, the combination with a punch, and a piston, of means for feeding rivets to a position in axial alignment with said punch and comprising, a gravity feed chute, an escapement device adapted to intercept the passage of the rivets through said chute and comprising a toothed tensioned plate extending into said chute and mounted for oscillating movement, and a lever for moving the plate in one direction and disposed in the path of said piston to thereby operate said escapement device.
